(57) **CLAIM**

The ornamental design for a vacuum conduit connector as shown and described.

DESCRIPTION

FIG. 1 is a perspective view of a first embodiment of a vacuum conduit connector showing the new design.

FIG. 2 is a front view thereof.

FIG. 3 is rear view thereof.

FIG. 4 is a right-side view thereof.

FIG. 5 is a left-side view thereof.

FIG. 6 is a top view thereof.

FIG. 7 is a bottom view thereof.

FIG. 8 is a perspective view of a second embodiment of a vacuum conduit connector showing the new design.

FIG. 9 is a front view thereof.

FIG. 10 is rear view thereof.

FIG. 11 is a right-side view thereof.

FIG. 12 is a left-side view thereof.

FIG. 13 is a top view thereof; and,

FIG. 14 is a bottom view thereof.

In these drawings, the solid lines illustrate the claimed ornamental design, whereas broken lines, if present, illustrate unclaimed subject matter and form no part of the claimed design. Stippling in the drawings is used to indicate a contrast in appearance, with no specific color, material, texture, or other feature being claimed.
